UNITED STATES PATENT OFFICE.

CLYDE S. WRIGHT, OF TOLEDO, OHIO, ASSIGNOR TO THE NATIONAL SUPPLY COMPANY,
OF TOLEDO, OHIO, A CORPORATION OF OHIO.

ROTARY WELL-DRILLING APPARATUS.

1,331,309.

Specification of Letters Patent.

Patented Feb. 17, 1920.

Application filed April 14, 1919. Serial No. 289,901.

To all whom it may concern:

Be it known that I, CLYDE S. WRIGHT, a citizen of the United States, residing at Toledo, in the county of Lucas and State 5 of Ohio, have invented new and useful Improvements in Rotary Well-Drilling Apparatus, of which the following is a specification.

My invention relates to rotary well-drilling and more particularly to devices for connecting the drilling string with a rotary table.

The object of this invention is to provide a plurality of drill-stems which may be 15 used in tandem, whereby a greater depth may be drilled before disconnecting the string and inserting additional sections to the string, than with the usual single section of drill stem. Another object is to 20 provide a novel means for connecting the drill stem and the rotary table. Other objects appear hereinafter.

Referring to the accompanying drawings, Figure 1 is a central vertical section of an 25 apparatus containing my invention, the drill-stems being in side elevation; Fig. 2, a central vertical section taken at an angle to that of Fig. 1; Fig. 3, a top plan view of the master-driver; Fig. 4, a side elevation 30 of the same; Fig. 5, a cross-section through the master-driver, the driver-bushing, and the drill-stem, the section being taken on the line V—V of Fig. 2; Fig. 6, a plan view of the driver-bushing; and Fig. 7, a 35 side elevation thereof.

On the drawings, 1 designates the rotary table resting on the tapered rollers 2 in the race 3 in the lower side of the table and in the race 4 in the upper side of the base 40 5. The base has a large central opening 6 in which the flange 7 on the lower side of the table fits. The table has a central opening 8 having its upper portion with a larger diameter, thereby forming the 45 shoulder 9 on which the table-bushing 10, which fits the opening 8, rests.

The table-bushing has the central vertical opening 11 which tapers downwardly to a point near the bottom of the bushing and 50 then flares to the bottom thereof. This bushing has also a pair of opposite vertical grooves 12.

13 is the master-driver. It is divided longitudinally, that is, vertically, into halves

which may be securely connected together by 55 the bolts 14 passed through the ears 15 on the respective halves of the master-driver. The latter extends through the opening 11 in the bushing 10 and fits the narrowest portion thereof. It preferably extends 60 somewhat above and below the table and has the horizontal flange 16 which rests upon the table-bushing 10 while a portion 65 17 just below the flange fits the adjacent part of the opening 11, whereby the master-driver is both supported and prevented from lateral movement. The master-driver 13 has also a pair of opposite lugs or keys 18 which are in the grooves 12 when this driver is in operating position, so that the 70 rotation of the table by means of the pinion 19 and teeth 20 on the under side of the table, causes the said driver to rotate also.

The master-driver 13 has a central vertical opening provided in its interior wall with a 75 number of preferably angular vertical grooves 21, which extend from the top thereof to the inturned annular flange 22 at the bottom thereof. The driver bushing or key 23 is slidable in the opening in the 80 master-driver 13 and has the longitudinal external ribs 24 which fit the grooves 21. The driver bushing 23 is divided into lateral halves, as shown on Figs. 5 and 6. It has a vertical opening extending entirely 85 through it and its internal wall is provided preferably with angular vertical ribs 25 opposite the ribs 24.

I show only a portion of a drilling-string. I show only two drill-stems 26 and 27 connected by the coupling 28, the drill being 90 carried by sections of tubing carried by the stem 27 in a manner well known. The drill stems and couplings are of a size to pass the flange 22. Each drill stem has 95 longitudinal grooves 29 corresponding in number, arrangement, and cross-section to those of the ribs 25 of the driver bushing 23. The grooves 29 stop short of the ends 100 of the drill-stems, or at least the lower end thereof, whereby shoulders 30 are provided for engagement with the ends of the ribs 25. The extreme ends of the drill-stems are reduced in diameter as shown at 31 so that the couplings 28 may be of a size to pass 105 the flange 22.

The drill-stem 27 having been lowered to the position occupied by the drill-stem

26 on Fig. 1, the halves of the driver bushing 23 are dropped into the master-driver 13 with the ribs 24 in the grooves 21 and with the ribs 25 in the grooves 29. The 5 drill-string is then operated in the usual way, the string descending until the driver bushing 23 reaches the flange 22 (Fig. 2), where it rests until the upper ends of the grooves come near to or reach the upper end 10 of the bushing 23. Then the string is lifted, the shoulders at the ends of the grooves 29 raising the bushing 23 until the latter is carried to the top of the master-driver 13 when the sections of the driver bushing 23 15 fall out or are removed. Then the string is lowered and when the drill-stem 26 reaches the position shown on Fig. 1, the driver bushing 23 is applied as before to connect the drill-stem 26 to the master- 20 driver 13. The operation proceeds as before, as long as there are any drill-stems left above to be used. Then the string will be raised and tubing will be inserted in the string below the drill-stems, and the drill- 25 ing operation will proceed as described.

In the ordinary drilling of wells, it is necessary from time to time to insert a length (about 20 feet) of drill pipe between the lower end of the drill-stem and the top 30 section of the drill-pipe. To do this it is necessary to raise the entire string until the upper end of the drill-pipe is above the table. The string has to be supported and the drill-stem removed and a new 20-foot 35 section screwed on. The drill-section has to be attached again and the string lowered to the drilling position when the drilling proceeds for another twenty feet. Then another twenty-foot section of drill-pipe 40 must be inserted in the string and so on during the drilling of the well. With my invention three twenty-foot lengths, for example, of drill pipe may be screwed together and inserted into the string. The 45 drilling can proceed until the well-hole has

been sunk sixty feet before it is necessary to insert any more drill-pipes.

The length of the master-driver 13 is preferably such that, when the upper ends of the grooves 29 in the lower drill-stem 50 reach the driver-bushing 23 resting on the flange 22, the lower ends of the grooves 29 on the next upper drill-stem have entered the master-driver sufficiently far to retain the section of the driver-bushing in place. 55

Various changes may be made in the shapes, sizes, and arrangements of the various parts of my invention without departing from the spirit of my invention as defined in the appended claims. 60

I claim:

1. In a rotary well-drilling apparatus, a horizontal rotary table having a vertical opening therethrough, a vertical tubular master-driver seated in the opening, having 65 non-rotatable connection with the table, and extended appreciably vertically beyond the table, a drill-stem in the master-driver, a pair of keys having sliding and non-rotative connection with both the master- 70 driver and the drill-stem, and means at the bottom of the master-driver for stopping the downward travel of the keys.

2. In a rotary well-drilling apparatus, a horizontal rotary table having a vertical 75 opening therethrough, a vertical tubular master-driver seated in the opening, having non-rotatable connection with the table, and extended appreciably vertically beyond the table, a drill-stem in the master-driver, a 80 pair of keys having sliding and non-rotative connection with both the master-driver and the drill-stem, and having travel below the top of the master-driver, and means at the bottom of the master-driver for stop- 85 ping the downward travel of the keys.

Signed at Toledo, Ohio, this 10th day of April, 1919.

CLYDE S. WRIGHT.
